UNITED STATES PATENT OFFICE

2,522,932

STARTING GATE

Harold C. Dressel, Batavia, N. Y.

Application June 18, 1947, Serial No. 755,366

4 Claims. (Cl. 119—15.5)

1

This invention relates to apparatus for assuring alinement of the race horses at the start of a race.

In the racing of horses, particularly in the type of racing known as harness racing, it has been the responsibility of the several drivers, under instructions of a track judge, to keep their several horses in alinement at the starting point. However, if the horses arrived at the starting point in misalinement, it became necessary for the judge to call back the drivers to try again to have their horses properly alined at the starting point. Frequently, a number of tries of this kind must be made before a "fair start" is achieved. Such "call-backs" are disturbing to the horses and annoying to the spectators who are interested only in the race and not in the maneuvers for the start.

The present invention has for its purpose a starting gate which will not frighten the horses, which will not materially obscure the view of the spectators and will be reliable.

The main feature of the invention relates to a starting gate which bridges or spans the course at an elevated position and which is guided to travel back and forth in a fixed path along the course.

Another feature of the invention relates to a starting gate movable under the control of the starting judge and provided with an obstruction which remains in the path of the horses until the starting point of the race is reached whereupon the obstruction is automatically moved out of that path.

An additional feature of the invention relates to a starting gate provided with driving means at each end thereof, both driving means being under the control of the starting judge.

Various other features and advantages of the invention will appear from the detailed description and claims when taken with the drawings in which:

Fig. 1 is a plan view of a portion of a race course provided with a starting gate arrangement of the present invention;

Figs. 2 and 3 are respectively a side elevation and a front elevation of a starting gate driven by a motor mounted thereon;

Figs. 3A and 3B are respectively a side view and a plan view of a starting post;

Fig. 4 is a diagrammatic showing of a circuit with the motors and apparatus for that type of starting gate which is advanced or reversed by a motor mounted thereon;

Fig. 5 is a fragmentary showing of a race course

2

arranged to use a modified form of the invention in which the gate is driven by cables;

Fig. 6 is a side elevation of a modified starting gate of the cable driven type;

Fig. 7 is a transverse section through the motor pits and also through the ground of the race course showing the motors and the related apparatus for driving the cables of this modified starting gate; and

Fig. 8 is a diagrammatic showing of an electrical circuit arrangement for operating the cable driven starting gate.

Referring first to Fig. 1, there is illustrated the straightaway portion of a race course, generally designated C, which is of the conventional shape and arrangement so that it can be used optionally for races either a mile in length or for races nine-sixteenths of a mile in length. The starting point for the mile race is indicated at S1 but the starting point for the shorter race is herein omitted for purposes of simplifying the description. In accordance with the preferred form of the present invention, as best shown in Figs. 2 and 3, there is provided an alinement or starting gate G which bridges the race course. The respective ends of the gate are provided with pairs of wheels 5 which travel on stationary channel-shaped guide tracks 6, one of which is mounted on a secure foundation at each side of the straight portion of the course. The gate is arranged to be driven at a selectively variable rate in order to keep it just ahead of the horses until the starting point is reached. The gate spans the width of the course at a considerable height above the same with a swingable obstruction 8 suspended so that its lower edge is in a position at approximately the height of the nose of the average horse. When, however, the gate reaches the starting point of the race, such as S1, a post 7 anchored in the ground engages means on the gate to trip the obstruction 8, causing it to swing upward to its dotted line position in Fig. 2 where it remains, so that the horses can pass through. The gate is then driven in reverse to its normal or home position.

Specifically the gate, at each end thereof, is formed with a truck comprising two spaced horizontal channel-shaped beams 8 (Figs. 2 and 3). The adjacent ends of these beams are secured to brackets 9, each bracket being provided with bearings in which there turns the axle 10 with a wheel 5 secured thereto. These wheels are preferably of the type that uses pneumatic tires so that noise will be eliminated. At an intermediate point on the pair of horizontal beams 8, there is

secured a vertical I-beam 11. This I-beam is maintained in a vertical position by inclined, channel-shaped braces 12 which extend from the respective ends of the truck to the respective ends of a horizontal cross-piece 13, secured to the upper part of the I-beam. A second horizontal cross-piece 14 is secured to the braces and to the vertical beam 11 in spaced relation below the first-mentioned cross-piece 13. The cross-pieces 13 and 14 serve as supports for a lattice truss 16 which extends from one vertical I-beam 11 to the other. From the under side of the truss but somewhat in advance thereof, there are mounted bearings 17 (Fig. 3) in which the movable obstruction 8 is supported to swing about a horizontal axis. This obstruction, as previously mentioned, serves as a means to line up the horses at the start of the race but is easily swung out of the way when tripped in the normal manner or when it is touched by a horse which has started to bolt. The obstruction includes a horizontal shaft 19 which turns in the bearings 17 and which extends a short distance beyond each of the vertical I-beams 11. This shaft terminates at each end in a bevel gear 20, the purpose of which will be described later. Connection T's 21 are secured in spaced relation along the shaft 19 at a distance apart to accommodate a horse. As herein indicated by way of example, there are eight spaces along the obstruction to accommodate eight starting horses. Suitable tubes 22 connected to the T's, project away from the mentioned shaft and are connected in any convenient manner to a horizontal cross-piece 23 made up of tube sections which extend parallel to the mentioned shaft 19. The obstruction is so made that when it is in its lowered position the cross-piece 23 will be located at approximately the level of the nose of a horse of average height.

It has been mentioned that each end of the shaft 19 is provided with a bevel gear 20 which projects beyond its adjacent vertical up-right or I-beam 11. Each bevel gear meshes with a second bevel gear 25 carried on the upper ends of a vertical shaft 26 which is mounted in suitable journals 27 secured to cross-supports 28 and 29 on each end of the gate. The lower end of each such vertical shaft 26 is provided with a crank arm 30 biased by spring 31 to project outwardly whereby the crank arms can engage the clips 1a, of a pair of starting posts 7 at point S1 at the respective sides of the course, when the starting point is reached. The clip 1a (Figs. 3A and 3B) on each post is horizontally adjustable so that the obstruction can be tripped at the exact point desired. When the respective arms 30 engage their respective pair of starting posts 7, they act as cranks which turn the vertical shafts 26 and acting through the mentioned bevel gears 20 and 25, swing the obstruction 8 into its upward position against the stop bar 32 as indicated in dotted lines in Fig. 2. Suitable rubber bumpers 22a on the obstruction engage the stop bar 32 to reduce the noise that would result if the several metal parts came into direct contact with each other. It will be noted (Fig. 3) that each end of shaft 19 is provided with a crank arm 19a. A coil spring 33 is connected to the free end of each crank arm and to the adjacent vertical I-beam 11. The arrangement of these springs 33 is such that the obstruction 8 will be held in its lower (full line) position (Fig. 2) or in its upper (dotted line) position, as the case may be.

It has been mentioned that the gate G with its obstruction, is advanced at a selectively variable

speed on the guide tracks 6 so that the obstruction 8 is maintained just ahead of the noses of the several horses in the race. For this reason suitable means are provided to operate the gate 5 under the guidance of the starting judge. The starting judge rides on a platform 34 provided at one end of the gate so that he can call out instructions to the several drivers in the race and at the same time advance the gate at a faster or slower rate as conditions require.

The gate is driven by motors M, M at each end thereof. One of these motors is mounted adjacent the platform 34 on which the judge rides and is driven from a storage battery B. An 15 electrically operated brake MB normally grips the motor shaft. The operation of this motor including starting, accelerating, and stopping thereof, is governed by a control box 35 which is provided with a controller having a handle 36 (Fig. 2 and with a reversing switch handle 37 within convenient reach of the judge. This 20 control box for the most part contains apparatus and circuits (diagrammatically shown in Fig. 4) which are adjusted by the mentioned controller 25 handle and reversing switch handle, as will be set forth in the description of the operation of the gate. Each of the motors M, M operating through the gear box 38, drives a vertical shaft 39 mounted in journals 40 at the respective ends 30 of the gate. Each shaft is provided at its upper end with a bevel gear 41 which meshes with a bevel gear 42 on the related end of the horizontal shaft 43 (Fig. 3). The shaft 43 is mounted in suitable bearings secured on the undersides of 35 the cross-bars 14. The horizontal shaft 43 has secured thereto beyond each end of the gate, a bevel gear 44. Each gear 44 meshes with a bevel gear 45 that is secured to the upper end of a downwardly inclined shaft 46 at each end of the gate. Each shaft 46 at its lower end has secured thereto a bevel gear 47 which meshes with beveled gear 48 secured to the axle 11 of one of the pairs of wheels 6 at each end of the gate. By the construction just described the motors M, M drive 45 both ends of the gate synchronously at the speed and in the direction chosen by the judge.

The operation of the system is as follows: At this time the gate G will be standing on the left end of the tracks 6. When the starting judge is 50 ready to start the race, he mounts the platform 34. Thereupon, he throws the handle 37 of the reversing switch to its forward position and turns the controller handle 36 in a counterclockwise direction to its second position. This operation 55 energizes the electromagnet Fig. 4 in the brakes MB to disengage the motor shafts. The motors are also energized to move the starting gate at its lowest speed. To increase the speed of the starting gate, the starting judge continues to turn the controller handle 36 in the counterclockwise direction, thereby cutting out sections of the rheostat R until the gate attains a desired speed. In the event that the judge wishes to slow down 60 the gate, the controller handle 36 will be turned back manually in a clockwise direction to the first position. This will slow down the gate but will not apply the brakes. When the starting gate reaches the official starting point, the arms 30 projecting from the gate engage the clips 1a on the starting posts 7, which it will be recalled are fixed in the ground at the starting point. When the crank arms engage these posts 7, the shafts 26 are given a partial turn which is communicated through the bevel gears 25 and 20 to the shaft 19. Shaft 19 as it rotates swings the 65

obstruction 0 to its raised position, indicated in dotted lines in Fig. 2. The springs 33 maintain the obstruction 0 counterbalanced in its elevated position. With the obstruction 0 thus raised, the horses can pass through the gate on their way around the race course. In the event that the gate has not been reversed when a predetermined point along the tracks 6, a projection 49 extending upward from the track is arranged to open the limit switch 50 in the circuit of the motor M. The motor will then cease to run in a forward position. However, by manually closing the limit switch and by throwing the handle 37 of the reversing switch into its alternate position, the starting gate can again be brought back to its normal or home position on the track since the motors M, M, will then be operated in their reverse direction. The motors will stop when the handle 36 moves the controller to its normal position as shown.

In the event that a horse starts to bolt, part of his body will contact the lower part 23 of the obstruction 0. Since this obstruction is counterbalanced by the springs 33, the obstruction will swing to its uppermost position and remain there until restored.

In the modified form of the invention shown in Figs. 5, 6 and 7, the motors M, M, and the storage battery B for driving the gate are omitted and instead the gate is moved by motor-driven cables 55 respectively extending along each side of a straight portion of the race course. Each of these cables is driven from a motor 56 (Fig. 7) located in a pit 57 at each side of the course. The shafts 58 of these two motors, are in alignment and are coupled together at 59 to extend under the course. The cable for driving each end of the gate has its ends connected to the respective ends of the truck. The portion of each cable connected to the right end of the truck (Fig. 6) is adapted to slide along the upper surface of the guide track 6 and is adapted after passing over an idler 60 to pass through a metal tube 62 buried in the ground and leading to the motor pit 57. At the pit several turns of each cable are wound around a driven pulley 63 and then passes over a guide 61 in contact with guide disk 61a to slide along the guide track 6 for connection to the left end of the truck. The driven pulley 63 is mounted on a stud shaft 64 which is adapted to turn in suitable bearings in the spaced uprights 65. The shaft has secured thereto a gear 66 which meshes with a gear 67 on the shaft 58 of the motors 56 which in turn drive the pulleys and drag the cables in one direction or the other so that the gate can be advanced or backed up at the will of the judge. The driving motors 56 in this modification are driven from a commercial source of current, for example, in the present instance, the source is 220 volts, three phase, sixty cycle current, which current is governed by the controllers 70a or 70b preferably located at one side of the course adjacent the mile starting point S1 and adjacent the nine-sixteenths starting point S2 (Fig. 8).

The operation of the modified form of gate will best be understood from the description of the circuit diagram of Fig. 8. It will be understood that the operation of this form of gate is similar to that described above except that a different propelling mechanism has been substituted. When the race is to be started with this modified gate, the starting judge takes his position at the controller 70a located, for example, at the starting point S1 of the mile course. The

gate will then be at the left end of the tracks 6. When the judge is ready to start the race, he closes the power switch 71, throws the switch 72a to its upper position and moves the handle of the controller 70a to its starting position. This completes a circuit for releasing the brake on the motor shaft 58, and for starting the motors 56 at low speed. Since the motors 56 and related apparatus, are operated in parallel, it will be necessary to describe the circuits for operating one motor only. It will be understood that the operating circuits for the second motor 56 will be similar to those of the first motor. The starting circuit may be traced as extending from the current source, over conductor 73, winding of the brake relay 74, conductor 75, controller contacts 76 (now closed), conductor 77 and through the contacts of switch 72a, conductor 78, through the limit switches 79, conductor 80 to one side of the current source. This circuit operates the brake relay 74 which in turn closes an operation circuit for the magnet winding of brake MB to release this brake. The operating circuit for the relay 82 that starts the motor, may be traced from the current source, conductor 73, winding of relay 82, conductor 83, contacts of switch 72a, conductor 84, controller contacts 85, conductor 77, contacts of switch 72a, conductor 78 and through the limit switches 79, conductor 80 to the other side of the current source. Relay 82 when energized, closes the operating circuit of the motor 56 by connecting the three power conductors through motor 56 and conductors 31 as well as through the rheostat sections Ra, Rb and Rc. This circuit starts the motor 56 in its low or first speed since the sections Ra, Rb and Rc of the rheostat are all included in the motor circuit. The two motors 56 will drive the cables to advance the gate in its forward direction. By turning the controller handle back to its first position wherein the contacts 76 only are closed, the motors will slow down but the magnets of brakes MB will remain energized so that the brakes will not be applied. To increase the speed of the starting gate, the judge will turn the handle 70a of the controller to the selected speed, the controller contacts 87, 88 and 89 being closed in succession where the highest speed is desired. Where the second speed is desired, the controller handle is turned to close the contacts 87. This completes a circuit for energizing the second speed relay 90 which operates to shunt a portion of the resistance sections Ra, Rb and Rc of the rheostat. If the third speed is desired, the controller handle is moved to close contacts 88. This completes a circuit for energizing the third speed relay 91, which operates to shunt out an additional portion of the resistance sections. Where the highest speed is wanted the controller handle is turned to close the contacts 89. This completes a circuit for energizing the high speed relay 93, which operates to shunt out all of the resistor sections Ra, Rb and Rc of the rheostat. The gate is thus advanced at the selected speed, until the crank arms 30 which project from the gate, engage the starting posts 7 at the starting point S1. This engagement moves the obstruction 0 to its second position, that is, out of the path of the horses. If the judge fails to throw the switch 72a to its reversing position before the limit switches 79 are reached, the projection 94 on the gate (Fig. 6) will open a pair of these switches which open the several operating circuits to stop the gate. When it is desired to

return the gate to its home position at the left end of the tracks 6, the switch 72a is moved to its lower position. The reverse relay 95 is then energized from one side of the power source, conductor 73, winding of the relay 95, conductor 92, lower contacts of switch 72a, conductor 95, through the reverse limit switches 98, conductor 80, to the other side of the power source. The reverse relay 95 is thus operated and at its contacts closes a circuit for operating the motor 56. It will be understood that the reverse relay 95 of the second motor 56 likewise completes a circuit for operating this motor also in reverse. These motors, therefore, move the gate in the reverse direction along the tracks 6 to the home position. The opening of the switch 72a, interrupts all of the relay circuits of the system so that the motors stop. If the operator fails to open the switch 72a before the left end of the tracks are reached, the projections 94 (Fig. 6) on the ends of the gate will open the limit switches 98 (Fig. 5) at the side of the respective tracks. This interrupts the several relay circuits to stop the motors and thereby bring the gate to rest.

If the course is utilized for a race nine-sixteenths of a mile in length, the switch 72b and the right hand controller (Fig. 8) which are located adjacent the starting points S2, are used. The operation of the gate from this controller, is similar to that already described and need not be repeated here.

What I claim is:

1. In an arrangement for maintaining race horses in alignment at the start of a race, in combination with a race course having a given starting point, a guide track at the inside and at the outside of a portion of the course extending at least to said starting point at approximately the level of the course, a gate comprising a horizontal support bridging the course at an elevated position and arranged to travel on said guide tracks, a horizontal shaft mounted on said support, a substantially rigid obstruction frame extending transversely of the race course, means including said shaft for moving said frame relative to said course from a position in which it obstructs the course for the passage of horses, to a second position in which it permits the horses to pass through on their way along the course, a stationary projection at said starting point, and means including a crank arm on said gate cooperating with said projection to rotate said shaft whereby said obstruction frame is moved to its second position.

2. In an arrangement for maintaining race horses in alignment at the start of a race, in combination with a race course, a guide track at the inside and at the outside of a substantial portion of the course, a gate spanning the course at an elevated position above the level of the horse's heads and arranged to travel on said guide tracks, means for advancing said gate along said guide tracks, said gate having mounted thereon a rigid obstruction frame arranged to move from a posi-

tion in which it obstructs the course for the passage of horses to a second position in which it permits the horses to pass through on their way along the course, and means responsive to active contact of a horse with said frame to move said frame to said second position.

3. In an arrangement for maintaining race horses in alignment at the start of a race, in combination with a race course having a given starting point, a guide track at the inside and at the outside of a portion of the course and extending along the same at least to said starting point, a gate comprising a truss bridging the course at an elevated position above the heads of the horses taking part in the race and arranged to travel on said guide tracks, a substantially rigid obstruction frame hingedly supported at a plurality of spaced points along the truss to extend transversely of the race course and arranged to move relative thereto from a position in which it obstructs the course for the passage of horses to a second position in which it permits the horses to pass through on their way along the course, means responsive to the arrival of said gate at said starting point for moving said frame to said second position and means responsive to active contact of a horse with said frame to move said frame to said second position.

4. In an arrangement for maintaining race horses in alignment at the start of a race, in combination with a race course, a guide track at the inside and at the outside of a substantial portion of the course, a gate spanning the course at an elevated position above the level of the horses' heads and arranged to travel on said guide tracks, means for advancing said gate along said guide tracks, said gate having mounted thereon a rigid obstruction frame arranged to move from a position in which it obstructs the course for the passage of horses to a second position in which it permits the horses to pass through on their way along the course, and means responsive to active contact of a horse with said frame to move said frame to said second position, said means including at least one spring tending to hold said frame in each of its respective positions.

HAROLD C. DRESSEL.
